UNITED STATES PATENT OFFICE.

LITTLETON W. TURNER, OF LINCOLN, AND LOUIS VAUGHAN, OF BLAIR, NEBRASKA.

EXHAUST-MUFFLER.

1,175,206.

Specification of Letters Patent. Patented Mar. 14, 1916.

Application filed December 26, 1913. Serial No. 808,812.

To all whom it may concern:

Be it known that we, LITTLETON W. TURNER and LOUIS VAUGHAN, citizens of the United States of America, the former 5 residing at Lincoln, in the county of Lancaster, and the latter residing at Blair, in the county of Washington, and both in the State of Nebraska, have invented certain new and useful Improvements in Exhaust-10 Mufflers, of which the following is a specification.

Our invention relates to improvements in mufflers for the exhausts of power engines driven by expansive fluid; and the objects 15 of our improvement are, first, to progressively and increasingly diminish the pressure of the pulsative discharge current in the exhaust duct, prior to an unobstructed final discharge at diminished pressure; sec-20 ond, to provide means for adjusting the muffler qualitatively, that is, to accord with the intensity of the exhaust; and, third, to provide means for quantitative adjustment: to accord with the size of the engine, its 25 connected exhaust duct and the volume of the exhaust.

These and other constructional objects hereinafter more particularly set forth, we attain by the structure illustrated in the accompanying drawings in which—

Figure 1 is a perspective view of a complete muffler as arranged to muffle an exhaust of medium or ordinary intensity and volume; Fig. 2, a fragmental top view of 35 the discharging end and its supporting yoke-hanger; Fig. 3, a fragmental longitudinal section on the dotted line 3 of Fig. 4; Fig. 4, a cross-sectional view on the broken line 4 of Fig. 5; and Fig. 5, a fragmental side elevation of such a muffler construction modified and enlarged for an exhaust of greater volume.

In all of which views like parts are designated by the same reference numerals.

An exhaust of greater volume, logically 45 requires a larger exhaust duct. And in a large pipe the proportion of area of cross-section or capacity to its circumferential measurement or wall superficies, is greater 50 than in a smaller pipe. This is a fact pertinent to the adjustment features of a wide-open muffler of the character herein set forth, and is taken into consideration in our solution of the muffler adjustment problem.

The exhaust pipe 5 has its walls at opposite sides slitted backwardly from its dis-

charging end to split the pipe axially and form the opposed integral elastic halves or tongues 6 and 7. This slitting,—preferably done with a very thin cutter, forming narrow slots through the wall of the pipe,—will complete the muffler in cases of very small pipes, if sufficient length of pipe is available to make the slots as long as required, and the wall of the pipe is thick 60 enough to resist the tendency to bend and set the tongues outwardly or to noisily vibrate then. In most cases, especially for a light exhaust with limited length of slot, an advantage is attained by supporting the 65 tongues bent outwardly, to widen the slots in a small degree, toward the discharging end, as shown in Fig. 1. To facilitate adjusting the bend of the tongues to increase or decrease the widening of the slots, in accordance with the exhaust requirements, an 70 adjustable yoke hanger is constructed as follows: A single piece of wire is bent intermediately to form the coils 8 and 9, single about the outside of the half or tongue 6, 75 and double about the outside of the opposite tongue 7. The end portions 10 and 10 of the wire are extended parallel with each other from the slots at opposite sides of the 80 tongues, by and beyond the tongue 6, and have their ends bent to form the terminal 85 eyes 11 and 11 to receive the attaching screws 12. The coils are spaced apart at the bases of the straight hanger portions 10, and a bolt 13 is inserted across between the 90 coils and through the slots across the exhaust duct. The coiled part of the wire forms an elastic yoke around the tongues, to 95 yieldingly bind them against the inserted bolt. By changing the position of the yoke, toward or from the discharging end of the duct, the inclination of the tongue-halves to each other is changed to modify the taper of the intervening slots; for greater changes bolts of different diameters are substituted 100 for the bolt 13, to fit which, the elastic yoke expands or contracts. To fasten the whole at any point of desired adjustment, the nut 14 is turned home, it and the bolt head 15 clamping the coiled wire firmly against the 105 adjacent edges of the tongues.

For an exhaust of greater volume, a larger pipe is slotted into three equal longitudinal tongues 16, 16 and 16, as shown in Figs. 4 and 5. These tongues are shown supported 110 by a modified yoke and hanger consisting of an integral cast metal ring 25 disposed

around the tongues and having the perforated lugs or ears 17 to receive the screws 18 threaded in the tongues to fasten them against the inside of the yoke. Athwart the 5 slots between the tongues, the yoke has the outward bends 19 having the chamfers 20 on their forward sides, so that the escape of the expanding fluid through the intervening slots 21 will not be obstructed by the 10 yoke. An extension 22 on the yoke-ring has the perforated ears 23, to receive the supporting bolts 24.

It is obvious that the discharging end of 15 an exhaust pipe may be varied as to size and slitted into any number of tongues, forming a like number of slots opening out endwise with said discharging end, in accordance with and as required by the volume or quality of the exhaust to be muffled.

20 We claim:

1. An exhaust muffler, comprising an exhaust pipe split longitudinally at its discharging end, a wire hanger and yoke coiled around the split portion of said pipe, a bolt 25 disposed through the split in the pipe and between the coils of the yoke-hanger at opposite sides of said pipe, and attaching eyes formed of bent portions of said wire.

2. An exhaust muffler, comprising a split 30 exhaust pipe, a yoke consisting of wire coiled around the split pipe, and a bolt disposed across through the split of the pipe and between the coils of the wire at opposite sides thereof.

3. An exhaust muffler, comprising an exhaust pipe having a portion of its discharging end split to form integral opposed elastic halves, an elastic supporting yoke disposed around the halves, and suitable 40 means to retain the halves bent away from each other against their resiliency and the resiliency of said yoke.

4. An exhaust muffler, comprising the discharging end of an exhaust pipe slitted to 45 form integral elastic tongues, an adjustable supporting yoke disposed about said tongues, and suitable means to retain the tongues bent outwardly against said yoke.

5. An exhaust muffler, comprising the discharging end of an exhaust pipe slitted to 50 form integral elastic tongues normally standing in the plane of its wall.

6. An exhaust muffler, comprising the open discharging end of an exhaust pipe, elastic 55 tongues disposed to form a continuation of

the exhaust duct at said discharging end, and suitable means connected to support the elastic tongues bent outwardly.

7. An exhaust muffler, comprising the discharging end of an exhaust pipe slitted into 60 longitudinally extending tongues and a yoke attached to rigidly support the extending ends of said tongues spaced apart.

8. An exhaust muffler, comprising an exhaust pipe having a portion at its discharging 65 end slitted into indetached sections, and a yoke attached to support said sections.

9. An exhaust muffler, comprising longitudinally-extended circumferentially-spaced 70 tongues disposed on the discharging end of an exhaust pipe in the plane of its wall.

10. An exhaust muffler comprising an exhaust pipe having its discharging end slitted into longitudinally extended circumferentially-spaced tongues. 75

11. An exhaust muffler, comprising a lengthwise portion of the discharging end of an exhaust pipe split into longitudinal indetached sections.

12. An exhaust muffler, comprising the 80 open discharging end of an exhaust pipe slitted to form integral tongues thereon.

13. An exhaust muffler, comprising a plurality of tongues based on and spaced around on the open discharging end of an 85 exhaust pipe.

14. An exhaust muffler, comprising an exhaust pipe having a plurality of longitudinal circumferentially-spaced open-ended slots extending through and backwardly 90 into the wall of its open discharging end.

15. An exhaust muffler, comprising an open discharging end portion of an exhaust pipe having a plurality of circumferentially-spaced slots extended through and backwardly 95 into its wall from said open discharging end.

16. An exhaust muffler, comprising an exhaust pipe having a plurality of slots through its walls and each slot open at one 100 end with the open discharging end of said exhaust pipe.

In testimony whereof we have affixed our signatures in presence of two witnesses.

LITTLETON W. TURNER.
LOUIS VAUGHAN.
